CHARLES F. MILLER, OF MOORES, PENNSYLVANIA, ASSIGNOR TO WESTINGHOUSE ELECTRIC & MANUFACTURING COMPANY, A CORPORATION OF PENNSYLVANIA

STOKER CONSTRUCTION

Application filed April 4, 1931. Serial No. 527,726.

My invention relates to progressive feed stokers of the multiple retort underfeed type and it has for an object to provide improved means for supporting the retorts and tuyères.

5 In accordance with my invention, I provide retorts including sectionalized side walls together with bottom walls made up at least in part by secondary ram structures. The tuyères covering the tuyère spaces between 10 the side walls and adjacent retorts are preferably supported by the upper edges of such adjacent side walls. My invention relates to improved beam or girder members for positioning and supporting the retorts and the 15 tuyères, the beams positioning and supporting the retort side walls so as to define alternate retort and tuyère spaces and the retort side walls supporting the tuyères at their upper edges. My improved beam structure comprises a plurality of abutting cast sections, 20 each section being of frame-like formation and having an upper compression member and a lower tension member spaced apart by strut member or members. Adjacent sections 25 are secured together by bolts including tension bolts located near the lower tension members of the abutting sections. In this way, a built-up cast beam structure may be provided of adequate strength and one which 30 does not require the use of intermediate supports. Not only is the strength of the beam provided for by the most advantageous location of the material composing it, that is, in spaced-apart tension and compression 35 members, but the compression members may be made relatively thin and of little depth, whereby the ingress of air into the tuyère spaces is facilitated throughout the length of such spaces and the open spaces between 40 the tension and the compression members provide for ready distribution and circulation of air throughout the space underneath the compression members of the girder beam structures. A more specific object of my 45 invention is to provide a structure having these advantageous features of construction and operation.

These and other objects are effected by my invention, as will be apparent from the fol-

lowing description and claim taken in connection with the accompanying drawings, forming a part of this application, in which:

Fig. 1 is a longitudinal sectional view through a retort of a stoker constructed in accordance with the present invention;

Fig. 2 is an enlarged plan view of the stoker shown in Fig. 1, illustrating the construction and arrangement of the retorts and tuyère rows, certain parts being omitted from portions of the stoker to illustrate more clearly the detail structure; and,

Fig. 3 is a fragmentary transverse section taken on the line III—III of Fig. 1.

Referring more in detail to the construction illustrated, the reference numeral 10 indicates, in its entirety, a stoker constructed in accordance with the present invention. The stoker comprises, in general, parallel alternately-arranged retorts 11 and rows of tuyères 12. Coal is fed from a hopper 13 and into the ends of the retorts by primary rams 14 reciprocating within ram boxes 15. The coal is advanced along the retorts and forced upwardly and laterally onto the tuyères by secondary rams 16 reciprocating longitudinally of the retorts. Air for combustion is supplied from beneath the stoker and flows horizontally through openings provided in the tuyères and into the fuel bed. The resulting ash is moved down the stoker by virtue of its frictional contact with the downwardly moving fuel bed and is discharged from the lower end by conventional means, not shown.

The stoker is supported at the front by a supporting construction 20 comprising a transverse girder 21 and a series of castings 22 disposed in abutting side-by-side relation along the upper face of the girder. The castings 22 are bolted to the girder 21. The stoker is supported at its lower end by a supporting construction 23 comprising a girder 24 and castings 25 disposed in abutting side-by-side relation and slidably supported by the upper face of the girder 24 so as to permit longitudinal expansion of the stoker.

The stoker is of a fabricated construction and comprises a plurality of spaced parallel beams 26 secured by bolts 27 and 28 at their

upper and lower ends respectively to the castings 22 and 25. A plurality of upright plates 29 are detachably secured by bolts 30 to each of the beams 26 to provide section-
5 alized retort side walls. The bottom walls of the retorts are provided by the secondary rams 16 and by detachably-mounted bottom or guide plates 31 supporting the secondary rams. The plates 31 are supported in position by brackets 32 which rest on upper lateral flanges 33 of adjacent beams and are bolted to the side plates 29. The tuyères 12 are disposed in overlapping stepped relation and bridge the distance between and are supported by the adjacent side walls of adjacent retorts.

It will thus be seen that the beams 26 which perform the load carrying function of the stoker, are separated from the burning fuel
20 by the sectionalized more refractory metal parts of the stoker, and are maintained in a cool condition by virtue of this contact with the air beneath the stoker. Furthermore, the beams are an inherent part of the retort structure and serve as a positioning means for the retort side walls, thereby determining the width of the air spaces between retorts.

Each beam is a frame-like construction and may be divided functionally speaking into
30 a compression member 40 which extends along the retort side wall and to which the side plates 29 are bolted, a tension member 41 connected at its ends to the member 40, and strut members 42 and 43 spacing or holding
35 apart the compression member and the tension member. Structurally speaking the beam comprises three integrally-cast frame-like sections 45, 46, and 47. The section 45 is secured by the bolts 27 to the casting 22
40 and comprises a compression section 40a, a tension section 41a and a strut section 42a. The section 46 comprises a compression section 40b, a tension section 41b and strut section 42b and 43b. The strut section 42b
45 abuts the strut section 42a and is rigidly secured thereto by bolts 48 and 49, the bolts 49 transmitting the tension stresses between the sections 41a and 41b thereby making them functionally speaking one member. The section 47 comprises a compression section 40c, a tension section 41c, and a strut section 43c, the latter section abutting the section 43b and rigidly secured thereto by bolts 50 and 51, the bolts 51 serving to transmit the tension stresses between the sections 41b and 41c making these two functionally one. The lower end of the section 47 is rigidly secured by the bolts 28 to the casting 25.

It will thus be seen that I have provided
60 an extremely strong and light beam for supporting and positioning the remaining parts of the stoker. The type of construction permits the use of relatively cheap material. Furthermore, due to the sectionalized feature, its length may be readily varied to suit

different length stokers by omitting the intermediate section, by varying the size of either of the sections, or by providing two or more intermediate sections. Also, as the beam is of frame-like design, a minimum amount of structure appears below the stoker in the air chamber, and thereby reducing to a minimum the likelihood of eddy currents in the air supply which if excessive cause uneven air distribution to the tuyères and a congested fuel bed.

From the foregoing, it will be apparent that I have devised a cast girder type of construction which makes possible the use of cast girders or beams for supporting very long underfeed stoker retorts without the use of intermediate supports. Heretofore, cast supporting beams constituting retort side walls have been used; however, such solid plate-like beams are not sufficiently strong to carry the stoker load if excessive spans between front and rear supports are involved. Therefore, I provide a girder type of beam which does not function as a retort side wall but serves only as a beam to carry load, the elements constituting the retort side walls being supported and positioned by the girder beams. Therefore, having relieved the cast beams of the duty of themselves providing retort side walls, it becomes possible to use the girder construction of the type herein disclosed wherein the extreme compression and tension fibers are located at such distances from the neutral axis as to provide a very strong structure for the amount of material used. As most of the material constituting the girder is embodied in the compression and tension portions and as such portions are located desired distances from the neutral axes as just pointed out, it will be apparent that the construction is very strong for the weight of material used and that it is therefore possible to provide a supporting girder which can be made relatively much longer than the type of cast iron retort side wall beam heretofore used.

While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claim.

What I claim is:

In a furnace, the combination of spaced supporting structures, parallel, alternately-arranged retorts and rows of tuyères providing an inclined multiple retort underfeed stoker extending between and carried by the supporting structures and comprising a plurality of pairs of longitudinally-extending, parallel beam members carried by the supporting structures, the beam members of each

pair being spaced apart so as to position the retort side walls to define alternately-arranged retort and tuyère spaces, each beam member comprising a plurality of abutting 5 cast sections and each section including upper compression and lower tension members spaced apart by compression strut means, and bolts for securing abutting sections together including tension bolts located adjacent the lower tension members of abutting sections.

In testimony whereof, I have hereunto subscribed my name this 2nd day of April, 1931.

CHARLES F. MILLER.
